(57) **CLAIM**

The ornamental design for a tip for demolition shear, as shown and described.

DESCRIPTION

FIG. 1 is an exploded right front perspective view of a tip for demolition shear of my new design, the replaceable portion being shown separated from the portion on which it is mounted, as are the fastening members;

FIG. 2 is a bottom right perspective view thereof in the assembled configuration, the bottom left perspective view being a mirror image thereof; and,

FIG. 3 is a partial cross section of a right elevation view taken along line 3—3 of FIG. 2, showing the front section of the replaceable portion.

The elements depicted in broken line segments of equal length form no part of the claimed design. The elements depicted in broken line segments of varying lengths illustrate the boundary of the claimed design.
